UNITED STATES PATENT OFFICE

JEREMIAH A. SULLIVAN, OF BROOKLYN, NEW YORK

GUARD FOR WINDOW POLES

Application filed November 2, 1927. Serial No. 230,445.

The present invention relates to a protective guard for the metallic heads of window poles of the type ordinarily employed to open vertically sliding windows or pivoted transoms. Poles of this type are frequently unwieldy and uncontrollable, especially in the hands of children, and are the cause of breakage of window panes when the pole-head strikes the window glass. The present invention aims to provide a resilient guard designed to prevent the breakage of window panes and which may be readily slipped over and attached to the heads of window poles now in general use without modifying in any way the structure of the pole-head. Its construction is quite simple, and it may be produced in large quantities at very little expense.

The invention will be more fully understood from the following description taken in connection with the accompanying drawings, in which:

Figure 1 shows a preferred form of the guard attached to a pole-head;

Figure 2 is a sectional view taken on line 2-2 of Figure 3; and

Figure 3 is a bottom plan view of the guard shown in Figure 1.

Referring to the drawings it will be seen that the pole 10, which is usually of wood, is provided at its end with a metallic head 11, secured to the pole by means of a screw 12. The head has the usual reduced shank portion 13 and angular projection 14, designed to engage a slot or opening in the window frame for the purpose of opening or closing the window. The head also has a pointed end 15, adapted to engage the window frame for closing the window. The resilient guard 40 which forms the subject matter of this invention has a general shape and contour conforming to the structure of the end of the metallic pole-head and comprises a neck portion 16, head 17 and an open flared end portion 18. The guard is preferably molded in one piece from a resilient and elastic material such as rubber, but it is understood that it may be reinforced where desired with inelastic material. The neck portion 16 is substantially cylindrical and is closed at one end, this

closed end forming the head 17 which is preferably thick in cross section to provide a resilient cushion at the end of the neck. The other end of the neck is open, the edge of the open end being angularly disposed to the axis of the neck to permit attachment of the guard to the pole-head. The open end portion of the guard is flared as shown at 19. This flared portion has an interior depression 20, adapted to co-operate with the pointed end 15 of the pole-head to hold the guard on the pole-head. The thickness of the flared portion 19 may be reinforced adjacent to the point of contact with the pointed end 15 to prevent the point 15 from forcing its way through the guard. The open end 18 is substantially elliptical in shape so that it fits closely to the shank of the pole-head, the edge having a circumferential bead to reinforce it and provide a relatively heavy elastic edge so that after the guard has been applied to the pole-head it is held securely thereon.

From the above description it will be seen that the metallic end of the pole, at least that portion which contacts with the glass in the window when improperly directed, is covered with a resilient guard which will effectively prevent breakage or marring of the glass in the window. Since it is customary in opening windows to direct the projection 14 towards the glass, this portion of the pole-head usually causes the greatest damage. The head 17, being relatively thicker than the remainder of the guard, will cushion the blow incident to sharp contact of the head with the window glass and prevent the metal head from breaking the glass. The point 15 is also covered with the guard and in turn engages the flared portion 19 to hold the guard on the pole-head.

Although the guard is designed to prevent the breakage of windows generally, it is particularly desirable in schools where poles of the type referred to are in use. In most schools the opening and closing of windows is taken care of by children in whose hands the poles are unwieldy. The guard is designed to fit the type of pole-head in general use, but it is intended that the present invention is susceptible to such modifications as will

enable the guard to be attached to other types of pole-heads.

Having described my invention what I claim is:

- 5 1. A guard for window poles comprising a neck and head portion and an elastic end portion adapted to engage the shank of the pole-head.
- 10 2. A guard for window poles comprising a neck portion and an elastic end portion adapted to engage the shank of the pole-head, said neck portion being provided with a resilient head.
- 15 3. A guard for window poles comprising an elastic neck portion, said neck portion having a resilient head at one end thereof, the other end thereof being open and provided with a reinforced edge, said edge being angularly disposed to the axis of said neck portion.
- 20 4. In combination with a window pole having a hook at one end thereof, said hook being formed with a shank and a solid portion, of a resilient nipple shaped to fit the hook portion and having a reinforced edge adapted
- 25 to engage the shank portion of the hook to hold the nipple in position on the same.

In testimony whereof, I have signed my name to this specification this 28th day of October, 1927.

30 JEREMIAH A. SULLIVAN.
